Primary Examiner — Susan Moon Lee(74) *Attorney, Agent, or Firm* — KORUS Patent, LLC; Seong Il Jeong(57) **CLAIM**

The ornamental design for an RFID reader, as shown and described.

DESCRIPTION

FIG. 1 is a rear, side perspective view of an RFID reader;

FIG. 2 is a front elevation view thereof;

FIG. 3 is a rear elevation view thereof;

FIG. 4 is a right side view thereof;

FIG. 5 is a left side view thereof;

FIG. 6 is a top plan view thereof; and,

FIG. 7 is a bottom plan view thereof.

The materials of the claimed design are synthetic resin, metal and rubber. The claimed design is portable, and is used to recognize the information of an RFID reader while being carried, if required.
